UNITED STATES PATENT OFFICE.

THOMAS M. DUDGEON, OF CRAFTON, PENNSYLVANIA, ASSIGNOR TO PITTSBURGH STOVE AND RANGE COMPANY, OF PITTSBURG, PENNSYLVANIA, A CORPORATION OF PENNSYLVANIA.

DESIGN FOR A FIREPLACE-FRONT.

SPECIFICATION forming part of Design No. 36,068, dated September 9, 1902.

Application filed July 29, 1902. Serial No. 117,587. Term of patent 7 years.

To all whom it may concern:

Be it known that I, THOMAS M. DUDGEON, a citizen of the United States, residing at Crafton, in the county of Allegheny and State of Pennsylvania, have invented a new, original, and ornamental Design for Fireplace-Fronts, of which the following is a full, clear, and exact description, reference being had to the accompanying drawing, forming part hereof, in which the invention is illustrated in front view.

The leading features of the design consist of a frame the sides and top of which have plain inner and outer border lines or edges. At the bottoms of the sides are scroll-like vase figures containing plants. Suspended from the tops of the side pieces are tasseled cords bearing casket-like figures. The cross-piece is in the shape of a hood having a central shell-like figure. The upper edges of the

hood where it joins the flat portion of the cross-piece is ornamented by diversely-extending scrollwork. The center or summer front has a border-like line near its outer edge entwined with sprays of grape-vine and depicts a winter landscape scene, with the figures of Cupid and a woman in the foreground kneeling beside an open fire. Below the summer front and extending between the side pieces is an open-work frame. 25 30

I claim—

The ornamental design for a fireplace-front as herein described and shown.

In testimony whereof I have hereunto set my hand.

THOMAS M. DUDGEON.
